UNITED STATES PATENT OFFICE

167,135

SALT SHAKER

Alexander R. Burton, Gloucester, Mass.

Application May 25, 1951, Serial No. 15,318

Term of patent 3½ years

(Cl. D44—22)

To all whom it may concern:

Be it known that I, Alexander R. Burton, a citizen of the United States of America, residing at Gloucester, State of Massachusetts, have invented a new, original, and ornamental Design for Salt Shaker, of which the following is a specification, reference being had to the accompanying drawing, forming a part hereof.

Figure 1 is a perspective view of a salt shaker, showing my new design;

Figure 2 is an elevational view of the same; and

Figure 3 is a plan view of the same.

I claim:

The ornamental design for a salt shaker, as shown.

ALEXANDER R. BURTON.
